ATTORNEY

UNITED STATES PATENT OFFICE.

PAUL M. PRUET, OF KANSAS CITY, KANSAS.

LEGGING.

Application filed November 17, 1922. Serial No. 601,505.

To all whom it may concern:

Be it known that I, PAUL M. PRUET, a citizen of the United States, residing at Kansas City, in the county of Wyandotte and State of Kansas, have invented certain new and useful Improvements in Leggings; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to leggings and the primary object thereof is to provide a legging which will protect the lower part of the trousers below the knee from rain, snow, sleet and the like.

20 It is well known that the moisture destroys the crease of the trousers because the part of the trousers below the knees is unprotected except when heavy ulsters or raincoats are worn.

25 My invention contemplates means for protecting the trousers below the overcoat or the present style of raincoat which generally terminates just below the knees. Therefore, the trousers will be protected against the rain so that they will preserve their fresh appearance. In other words, the legging is particularly a dress legging to protect the trousers so that they will not become wrinkled and to this end it generally conforms to the shape of the trousers leg and it is supported by the shoe, as will be apparent by reference to the following description in connection with the accompanying drawings, in which—

30 Fig. 1 is a perspective view of a pair of leggings applied, parts being broken away to show the manner of attaching, etc.

Fig. 2 is a detail perspective view of the collapsible, vertical, form-preserving brace.

35 Fig. 3 is a detail view of the legging detached and ready to be collapsed.

Fig. 4 is a detail view of the shoe-attaching means, and

40 Fig. 5 is a detail perspective view of the legging folded up.

One of the objects of this invention is to provide a legging which can be conveniently collapsed and folded so that it can be carried in the pocket when not in use.

45 The invention is illustrated as consisting of a substantially rectangular sheet 1, to

which is secured a brace consisting of the bars 2 and 3. The two bars 2 and 3 are telescopically secured one to the other by a loop 4 on the end of the bar 2 and embracing the bar 3, and a loop 5 on the lower end of the bar 3 and embracing the bar 2. In order to keep the bars extended when in functional position I have shown a spring detent 6 struck up from the bar 2 so that when the bars are in the position shown in Fig. 2, they cannot collapse but when it is necessary to collapse them, that is, to telescope them one upon the other, the spring detent 6 will be pressed in so that the loop 5 can ride over it. Then the two bars can be telescoped in parallelism so that they will be practically half the length shown in Fig. 2.

The brace bar 3 is provided with a clasp head 7, adapted to engage a fastener socket 8 on the upper portion of the sheet 1. The fastener may partake of the form of a well known glove fastener although other fastening devices may be employed if desired.

The lower end of the bar 2 is provided with a spaced wall member 9 to provide a space 10 between it and the lower end of the bar, in which is an inverted U-shaped spring 11, consisting of two legs, the leg 12 being fastened to the bar 2 and the leg 13 having a yielding action with respect to the leg 12 so that the clasp formed by the spring may engage the upper edge 14 of a shoe, for example, 15, to secure the brace thereto. In order that the brace may be fastened to the upper of the shoe 15, I provide a cam lever 16 which is pivoted in the wall 9 and which will press against the leg 13 to bind the upper of the shoe between it and the leg 12. The cam lever is releasable to permit the brace to be detached from the shoe.

The brace is fastened to the sheet 1 by the diametrically opposite fastening devices 17 and 18 and by stitching 19, passing through the holes 20 of the bar 2 and through the leg covering or sheet. The central portion of the sheet 1 is approximately the width of the trousers leg and there are two flaps 21 and 22 which are substantially half the width of the trousers leg. One of the flaps is provided with a fly 23 in which are headed projections 24, to be engaged by the spring socket members 25. The members 24 and 25 can be the respective members of a glove fastener if desired. The flap 26 will overlap the fastening devices 25 so as to obscure them from view.

Ordinarily the leggings will be carried collapsed so that they will assume the general appearance shown in Fig. 5. The collapsing is accomplished by detaching the head 7 from the socket 8 and sliding the bar 3 down upon the bar 2. Then the sheet 1 can be folded transversely as indicated by the dotted line 27 and the flaps 21 and 22 folded over toward each other. Then another longitudinal fold can be made if desired, so that the legging will take up a comparatively small amount of space and it will readily fit in the pocket.

When it is desired to render the legging available, the sheet will be spread out as shown in Fig. 3, the bar 3 will be extended so that the head 7 will engage the socket 8 and the legging can be applied first by fastening the bottom of the bar 2 to the upper of the shoe and then folding over the flaps 21 and 22 and securing them together. The fold lines 28 and 29 of the sheet will conform to the front and back creases of the trousers and since the leggings will be long enough to extend up to about the knees and under the skirt of the top coat 30, it will be apparent that the trousers below the knees will be protected from the inclement weather.

What I claim and desire to secure by Letters-Patent is:

1. A collapsible legging comprising a brace consisting of two members, one of which is slidable on the other, means for

holding the brace members distanced, a shoe-engaging clasp at the lower end of one of the members, and a legging fabric connected to the brace.

2. A collapsible legging comprising a brace consisting of two members, one of which is slidable on the other, means for holding the brace members distanced, a shoe-engaging clasp at the lower end of one of the members, and a legging fabric connected to the brace, the top of the fabric being detachably secured to the top brace member so that the top brace member can be telescoped on the bottom brace member and so that the fabric can be folded transversely to make a relatively small package when the legging is not in use.

3. A trousers legging comprising a brace consisting of two telescopic members, one of which is provided with a shoe-engaging spring clasp, a sheet removably fastened to the top member and permanently fastened to the lower member, and means for connecting the longitudinal edges of the sheet.

4. A legging comprising a brace consisting of two members, one of which is movable with respect to the other, a sheet permanently attached to one member and removably attached to the other member, and means for fastening the edges of the sheet together.

In testimony whereof I affix my signature.

PAUL M. PRUET.
